UNITED STATES PATENT OFFICE.

CARLETON ELLIS, OF MONTCLAIR, NEW JERSEY, AND MORTIMER J. COHEN, OF NEW YORK, N. Y., ASSIGNORS, BY MESNE ASSIGNMENTS, TO SETH B. HUNT, TRUSTEE, OF MOUNT KISCO, NEW YORK.

PROCESS OF DIRECTLY ESTERIFYING OLEFINS AND PRODUCT THEREOF.

1,365,052.

Specification of Letters Patent. Patented Jan. 11, 1921.

No Drawing.

Application filed June 30, 1916. Serial No. 106,769.

To all whom it may concern:

Be it known that we, CARLETON ELLIS and MORTIMER J. COHEN, citizens of the United States, and residents of Montclair, county of 5 Essex, and State of New Jersey, and New York, county of New York, and State of New York, respectively, have invented certain new and useful Improvements in Processes of Directly Esterifying Olefins and 10 Products Thereof, of which the following is a specification.

Our invention relates to the esterification of olefins and the products of esterification.

One object of the invention is the provision of a process by means of which an organic acid, such for example, as acetic acid or formic acid, may be combined directly with an olefin or olefins, even in the presence of saturated hydrocarbon diluents, such, for 20 example, as volatile hydrocarbons of the paraffin series or similar body or bodies.

Another object of the invention is the production of solvent mixtures, suitable for use in pyroxylin and related industries, directly 25 from petroleum products containing saturated and unsaturated materials by the esterification of the unsaturated olefins without the necessity of making a separation between such materials, although, if desired, 30 the esters and the saturated material, as gasolene, may be separately recovered.

While our invention may be applied to olefin materials separate from saturated petroleum materials, as gasolene and the 35 like, it is preferably carried out with a mixture of saturated and unsaturated materials, such as cracked gasolene, obtained by cracking heavier petroleum oils in any of the various modes available therefor, or other petroleum products containing mixtures of saturated and unsaturated material, as still gas condensate, and other similar bodies containing substantial quantities of the unsaturated olefins.

45 We have found that when olefins or mixtures of such saturated and unsaturated materials are treated with an organic acid, such as acetic acid, under apparently favorable conditions for reaction, such as the provision 50 of an excess of the acid, or the application of heat, as by means of heating under a reflux condenser over considerable periods, substantially no esterification of the olefins takes place, and that in the absence of suit-

able material as hereinafter set forth, in addition to the olefins and the organic acid or acids, which it is desired to unite, no substantial results can be obtained in the way of combining the organic acid with the unsaturated material.

60

We have found, however, that when a proper activating third material or substance is present, such direct addition of the organic, as acetic, acid or a mixture of organic acids to the olefins may be effectively 65 carried out, and we have found that among the activators having this effect concentrated sulfuric acid up to, say, about 10% or more of the acetic acid used is effective as an activator in bringing about the desired reaction. Other activators may, of course, be used, as, for example, hydrochloric acid, 70 phosphoric acid and other materials and substances which have the effect of bringing about the desired reaction.

75

The presence of water appears to be unfavorable to such direct addition reaction, and for this reason the organic acid used should be in substantially anhydrous state, as when acetic acid is used the acid should be 80 glacial acetic, and for other organic acids the acid should be as nearly as possible in the anhydrous state.

The glacial acetic acid used, when an acetic ester or esters is or are to be made, 85 may be either in substantially pure form, as may be prepared in advance, or a salt of acetic acid may be utilized, as calcium acetate, and this salt reacted upon by an acid as sulfuric acid, forming a pasty mixture of 90 calcium sulfate and the glacial acetic acid.

In working on mixtures of saturated and unsaturated materials, such as cracked gasolene, containing olefins with acetic acid, such petroleum mixture and the glacial acetic 95 acid or glacial acid containing material such as prepared from calcium acetate in the manner described are mingled together, as by adding either to the other, the acetic acid being preferably in excess of the amount required for acetylation of the olefins of the petroleum material, and an activator as concentrated sulfuric acid of preferably specific gravity of about 1.8 is added to the mixture, or vice versa, and the amount of such sulfuric acid may be up to about 10% of the quantity of acetic acid used, care being taken 100 preferably, however, to see that sufficient

105

concentrated sulfuric acid is present to take up any water which may be present without material dilution of the sulfuric acid to, say, below specific gravity of 1.7 or at least a 5 point not as low as specific gravity 1.57. The activator may be applied when a salt of the organic acid is utilized, as above, by providing a suitable excess of sufficiently strong sulfuric acid in making the glacial 10 acetic acid, it being unnecessary in such case to supply the activating sulfuric acid separately.

These materials may be placed in an apparatus such as a digester equipped with a 15 reflux condenser, and after heating, say, for a period of a couple of hours or so, and under atmospheric pressure or in some cases under super-atmospheric pressure, the esterification of the olefins by the organic 20 acid will have progressed in large measure or to substantial completion.

After the reaction has been completed to a sufficient extent the excess acetic acid and sulfuric acid may be removed by washing, 25 and the wash waters may be siphoned or otherwise taken off and the acids suitably recovered, if desired, and the salt, as calcium sulfate, if present, may be separated out as by centrifuging, filtration and the 30 like operations, and the materials remaining, consisting in part or principally of the esters of the various olefins, which, in the case mentioned, are the acetates, the saturated hydrocarbons originally present with 35 traces of free olefins remaining and small quantities of polymers of the olefins and sulfonated tarry bodies formed by the action of the sulfuric acid on the olefins, may be subjected to fractional distillation and 40 separated. If a fraction of cracked material is used having a boiling point of, say, below 100° C., the acetates corresponding to the olefins thereof boil approximately between 100° and 200° C., generally above 45 115° C., so that the material going over up to, say, 100° C. consists principally of unsaturated hydrocarbons with traces of olefins in their unchanged condition, and at temperatures of 115° and above the acetates may be separated and at substantially 50 higher points the polymerized bodies, which consist of heavier oils, as kerosene, lubricating oil and the like, leaving the tarry and sulfonated bodies in the condenser and 55 which may be discarded or distillation carried on until the residue has been distilled or coked.

Or to obtain the acetates in substantially pure form separation by sulfuric acid of sp. 60 gr. 1.57 may be resorted to in place of separation by fractional distillation, the esters being soluble in sulfuric acid of this strength in which the hydrocarbons, including such olefins as may be present, are in 65 soluble and may be separately drawn off.

By then diluting the sulfuric acid solution of esters to a point to bring the acid substantially below sp. gr. 1.57 the esters are separated from solution and form a top layer which may readily be drawn off or beneath which the weak acid may be drawn off from below. Then if desired the esters may be further purified by distillation and any traces of esters left in the weak acid 70 may be similarly recovered as well as any 75 esters left in the hydrocarbon material. The dilute acid may be concentrated for reuse.

In the above and other ways substantially pure esters may be obtained and separately recovered either singly or as a mixture of 80 esters from olefins or mixtures from hydrocarbon materials containing olefins or mixtures of olefins.

It is not essential, however, that there be such separation from the saturated gasolene 85 or other saturated material, for in many arts, as in the dissolving of guncotton, it is common to resort to the use of mixed solvents containing a substantial quantity of saturated material such as gasoline, and 90 for such uses suitable mixed solvents may be prepared directly without the necessity of resorting to separation work such as described.

In the production of such ready mixed solvents the fact that the cracking process may be controlled so as to govern the proportion of olefins produced is of importance. As is well known, cracking under comparatively low pressures tends to produce cracked material rich in olefins, while higher pressures tend to produce a relatively larger proportion of saturated material, and there are other conditions subject to control which affect the relative proportions of saturated 100 and unsaturated materials yielded and which need not be referred to in detail here, the important fact being that it is possible to control the relative proportions of saturated and unsaturated materials produced. 105

Accordingly, when a solvent containing specified proportions of, say, gasoline and acetates of the olefins is desired, it is only necessary to provide a cracked gasoline containing substantially the desired proportion 115 of olefins and to directly acetylate the olefins when the resulting material becomes available for use as a mixed solvent with only, of course, the necessity of separating out any excess organic acid used, together 120 with the activating material, as sulfuric acid, and the removal of any salts, as calcium sulfate, which may be present, or, if desired, the hydrocarbons and esters may be separately recovered, and when separately and sufficiently freed of undesirable materials may again be commingled to serve their solvent uses, with or without the addition of other solvents, as in a case where a more complex solvent formula is being 130

followed. In this way very substantial economies in the production of mixed solvents may be effected.

The direct production of esters by the union of an organic acid with the olefins and the obtaining of results such as outlined above is dependent upon the presence of an activating material in bringing about the reaction. As such activating material in the case of sulfuric acid referred to is substantially completely recovered, its action may be considered at least in a broad sense to be that of a catalyst, and it is with this property in view of bringing about the desired reaction while still being recovered in substantially its original condition that the term "catalyzer" is made use of in our claims. By such use, however, we are not to be understood as excluding the possibility of intermediate reactions taking place, the ultimate result of which may be, so far as the activator is concerned, to restore it to its original condition when the desired reaction resulting in the addition of the organic acid or acids to the olefin or olefins has been effected. Thus when using sulfuric acid in this capacity, alkyl sulfuric acid may be formed in some cases as an intermediate product.

We are not to be limited by the following example given as an illustration and for affording a clear understanding of one way in which the invention may be carried out. For example, other activators may be used than stated, so long as they have the effect of bringing about the desired direct reaction, and other organic acids and hydrocarbon materials may be used, and when sulfuric acid is used as an activator substantially smaller quantities than stated may be used, so long as the organic acid is kept substantially anhydrous. We have obtained good results with lesser quantities of sulfuric acid than 10%, and, if desired, more of the sulfuric acid may be used, it being desirable, however, not to make use of unduly large quantities of such mineral acid because of the tendency in such case of the olefins to become sulfonated and to produce objectionable tarry materials and heavy polymers of the olefins, which are preferably avoided so far as may be.

Following is an example showing one way in which the invention may be carried out: A mixture was made of about 20 parts of cracked petroleum material boiling below 100° C., about 100 parts of glacial acetic acid and about 10 parts of sulfuric acid of 1.8 specific gravity. The mixture was homogeneous and clear and on heating assumed a dark greenish color. The entire mass was heated under a reflux condenser for three hours and at the end of this time was washed with water to remove any excess of sulfuric acid and glacial acetic acid. The remaining

oil, which was dark red in color, was treated with sodium carbonate solution to neutralize any excess acid retained. This oil had the odor of the acetates and its saponification number was equal to 174, which indicates 45% acetate content referred to hexyl acetate. It is evident then from the foregoing acetate content that practically 100% conversion was obtained, viz: Substantially all the olefin material contained in the original cracked oil amounting to approximately 45% was converted into acetate. This oil dissolved pyroxylin very rapidly and on distillation the distillate was water-white, the boiling points of the product lying mainly between 125-160. Ready separation was made by this simple distillation method, since the original cracked material boiled mainly below 100° and contained principally simple normal olefins. However, if contaminated by unsaturated hydrocarbons retained, they may be separated out with sulfuric acid of 1.57 sp. gr., which may be added to the mixture of acetate and hydrocarbon oil, the former being dissolved by the sulfuric acid and the latter left untouched and subsequently separated and the mixture of acetates recovered by simply adding to water and collecting the liberated acetates.

Where adding one material to another is referred to in our claims, the use of this term or similar expression includes bringing the materials together in any preferred way, or in any order; and by the use of the term "heating" in our claims is meant the application of heat sufficient to bring about the desired reaction.

Having thus described our invention, we claim:

1. The process of making ester material which consists in combining by heating a fatty acid with an olefin hydrocarbon in the presence of an acid catalyst.

2. The process of making ester material which consists in combining, by heating at atmospheric pressure, substantially anhydrous acetic acid with an olefin hydrocarbon in the presence of a small quantity of sulfuric acid.

3. The process of making composite ester material which consists in combining, by heating at atmospheric pressure, substantially anhydrous acetic acid with a complex mixture of olefin hydrocarbons in the presence of sulfuric acid.

4. The process of making solvent material which consists in combining an organic acid with a complex mixture of olefin hydrocarbons in the presence of a substantial portion of saturated hydrocarbons by heating with a catalyst.

5. The process of making solvent material which consists in directly uniting by heating an organic acid with the olefins con-

tained in cracked gasolene in the presence of an acid catalyst.

6. The process of making solvent material which comprises converting cracked gasolene containing saturated and unsaturated hydrocarbons into a mixture consisting substantially of saturated gasolene and acetates corresponding to unsaturated hydrocarbons by heating with substantially anhydrous acetic acid at atmospheric pressure 5 in the presence of a small quantity of sulfuric acid not exceeding 10% of the acetic acid used.

7. The process of making solvent material which comprises directly converting cracked gasolene containing saturated and unsaturated hydrocarbons into a mixture consisting substantially of saturated gasolene and acetates corresponding to unsaturated hydrocarbons by heating such gasolene with acetic acid at substantially atmospheric pressure 10 in the presence of a catalyst comprising sulfuric acid.

8. The process of making solvent material which comprises directly converting cracked gasolene containing saturated and unsaturated hydrocarbons into a mixture 15

consisting substantially of saturated gasolene and acetates of unsaturated hydrocarbons by heating with substantially anhydrous acetic acid at atmospheric pressure 30 in the presence of a small quantity of sulfuric acid not exceeding 10% of the acetic acid used.

9. The process of making solvent material which comprises heating a hydrocarbon liquid, containing a substantial proportion of olefin hydrocarbons, with an excess of acetic acid, in presence of sulfuric acid.

10. A mixed solvent comprising saturated hydrocarbons, and a mixture of the esters 40 corresponding to the olefins of cracked gasolene.

11. A mixed solvent comprising saturated hydrocarbons, and a mixture of the acetates corresponding to the olefins of cracked gaso- 45 lene.

In testimony that we claim the foregoing, we hereto set our hands, this 28th day of June, 1916.

CARLETON ELLIS.
MORTIMER J. COHEN.
